DESIGN FOR A LAMP

Ray A. Schober, Chicago, Ill., assignor to Premium Products Mfg. Co., Chicago, Ill., a partnership composed of Ray A. Schober and Nate Asher

Application February 18, 1938, Serial No. 75,244

Term of patent 3½ years

To all whom it may concern:

Be it known that I, Ray A. Schober, a citizen of the United States and resident of Chicago, in the county of Cook and State of Illinois, have invented a new, original, and ornamental Design for a Lamp, of which the following is a specification, reference being had to the accompanying drawing, forming a part thereof.

Fig. 1 is a front elevational view of a lamp showing my new design.

Fig. 2 is the top view of the same.

Fig. 3 is a side view of the same.

I claim:

The ornamental design for a lamp, substantially as shown.

RAY A. SCHOBER.
